COOLING APPARATUS

Frank P. Taucher, Clayton, Mo., assignor to Westinghouse Electric & Manufacturing Company, East Pittsburgh, Pa., a corporation of Pennsylvania

Application May 29, 1935, Serial No. 24,001

8 Claims. (Cl. 62—126)

My invention relates to refrigerating apparatus, more particularly to such apparatus including a plurality of evaporator passages arranged in parallel with respect to refrigerant flow, and it has for an object to provide improved apparatus.

Another object is to supply liquid refrigerant to said evaporator passages in substantially equal proportions, or in any other desired proportions.

In a mechanical system of refrigeration, as the pressure of the condensed refrigerant is reduced before admitting the same to the evaporator, a portion of the refrigerant is vaporized, producing a mixture of liquid and vaporous refrigerant. For certain purposes, such as for comfort cooling of air, it is desirable to use an evaporator comprising a plurality of coils or evaporator passages, which are designed to do equal amounts of cooling. When the inlet ends of the evaporator coils are connected to the bottom of a header into which the mixture of liquid and vaporous refrigerant is admitted for distribution to the coils, it has been found that some of the coils receive mostly liquid refrigerant while others will receive mostly vaporous refrigerant. Due to the fact that the vaporous refrigerant has done most of its work in cooling the liquid refrigerant by the absorption of heat of vaporization, it has relatively little cooling capacity, and the coils receiving mostly vaporous refrigerant will be relatively warm and ineffective to do cooling.

In accordance with my invention, I provide a refrigerant supply header, and a plurality of evaporator passages whose inlet end portions project vertically into the header and terminate in a common plane between the upper and lower extremities of the interior of the header. Preferably, said inlet end portions project upwardly through the bottom of the header but they may project downwardly through the top of the header. A body of liquid refrigerant is thus accumulated in the header from which the evaporator passages receive liquid in equal proportions when the evaporator passages are identical, or in predetermined portions when they are not alike.

The above and other objects are effected by my invention as will be apparent from the following description and claims taken in connection with the accompanying drawing, forming a part of this application, in which:

Fig. 1 is a diagrammatic view of refrigerating apparatus embodying my novel evaporator, the latter being shown in side elevation;

Figs. 2 and 3 are end views of the left and right hand ends of the evaporator as seen in Fig. 1; and

Figs. 4 and 5 are detail views of two modifications of a detail.

Referring to the drawing in detail, I show an evaporator 10 disposed in an air duct 11, with the coils extending across the duct. A fan 12, driven by a motor 13, circulates the air through the duct and over the cooling surfaces of the evaporator. The evaporator comprises a plurality of coils 14, five such coils being shown. Each coil comprises tubes or convolutions 15 to 23, inclusive, through which the refrigerant flows successively, the adjacent ends of the successive tubes being connected by connecting portions 15'. As shown on the drawing, the tubes 15 to 19 are arranged in one horizontal row so that the air flows over the tubes in the order named, and the tubes 20 to 23 are arranged in a row immediately below the first row and so that air flows over the coils inversely of the order in which refrigerant flows therethrough. The several coils are arranged in superposed relation, so that they are in parallel with respect to air flow. This arrangement of the coils in the evaporator is disposed and claimed in the application of E. R. Wolfert, Serial No. 702,387. Plates or fins 23' are preferably applied to the tubes, extending transversely thereof, for the purpose of providing extended heat transfer surfaces, as is old and well understood in the art.

The tubes comprising the coils are mounted in end walls 24 and 25, connected by top and bottom walls 26 and 27, said four walls forming a chassis or frame structure for the evaporator. The front and back sides are open to provide for flow of air over the coils.

A refrigerant supply header or manifold 28 is provided, being disposed in the illustrated embodiment adjacent the upper edge of the wall 25. The several coils are provided with inlet end portions 29, connected to the inlet ends of the tubes 15 of the several coils. Said inlet end portions 29 project upwardly through the bottom of the header 28 into the interior thereof, and terminate intermediate the upper and lower extremities of the interior of the header, as shown in Figs. 1 and 3. The upwardly opening inlet ends are disposed at substantially the same level, that is, substantially in a common horizontal plane. The outlet ends of the several coils, that is, the outlet ends of the tubes 23, are connected to a suction header 30 through tube portions 30'. In the present embodiment, the coils 14 are identical in dimensions and construction, and the inlet end portions 29 are of identical circular cross-section, though of varying length.

The refrigerating unit for supplying the evaporator with refrigerant includes a compressor 31 driven by a motor 32. The inlet of the compressor is connected through a conduit 33 with the suction header 30, and the outlet thereof is connected through a conduit 34 to a condenser 35. The latter discharges into a liquid receiver 36 from which liquid refrigerant is conveyed through a conduit 37 to an expansion valve 38. The expansion valve 38 may be any suitable pressure reducing device known in the art, but I prefer to use a device of the type known as a thermostatic expansion valve which includes a thermostatic bulb 39 connected thereto through a tube 41 and responsive to the temperature of the vaporized refrigerant returned to the compressor. Such a device controls the flow of refrigerant so as to maintain a pressure on the discharge side of the valve which is in predetermined relation to the temperature of the vaporized refrigerant; in other words, to maintain a constant degree of superheat of the vaporized refrigerant returned to the compressor.

The refrigerant discharged at low pressure from the expansion valve is conveyed through a conduit 42 to the refrigerant supply header 28 of the evaporator 10. The conduit 42 may be connected with the header 28 at any suitable point, but preferably it is connected to the bottom thereof intermediate two of the inlet portions 29, as shown in Fig. 3.

The operation of the above-described apparatus is as follows:

Vaporized refrigerant discharged from the coils is conveyed through the conduit 33 to the compressor wherein it is compressed. It then flows through the conduit 34 to the condenser 35 in which it is reduced to liquid state and delivered to the liquid receiver 36. From the latter, it flows through the conduit 37 to the expansion valve 38, which is controlled as mentioned above. As the refrigerant passes through the expansion valve, its pressure is reduced, causing a portion of the refrigerant to be vaporized in reducing the temperature thereof to the saturation temperature corresponding to the reduced pressure. The mixture of liquid and vaporized refrigerant flows through the conduit 42 to the refrigerant supply header 28. The vaporous refrigerant enters the header in a turbulent state. Part of the vapor segregates from the liquid and goes to the top immediately. A portion of the gas remains suspended in the liquid and bubbles out as the liquid seeks the bottom level. In the present case the liquid and suspended gas collect in a body 43 having a definite level, indicated on the drawing 44, while the vapor as it collects and bubbles off fills the pocket 45 above said level. This level 44 is just above the inlet ends of the evaporator coils or passages, which are at the same level, so that the liquid flows over the end edges thereof into the coils, while the vapor enters the central portions of the inlet ends of the coils. Inasmuch as the several coils have equal perimeters at the inlet ends, the quantities of liquid received will be equal, as will also the quantities of vapor. When the inlet ends are not equal, they will receive liquid refrigerant substantially in proportion to the perimeters of their inlet ends. The header 28 should be sufficiently large, relative to the coils 14, to obtain a velocity of refrigerant fluid in the header which is sufficiently low to permit the liquid to acquire a substantially placid liquid surface.

For example, in an evaporator for a 2 or 4 ton

refrigerating system, the header 28 may have an inside diameter of 1.25 inches.

The liquid level 44 is maintained substantially constant, just above the inlet ends, since any tendency to drop will result in an accumulation 5 of liquid which brings the liquid level up, while a tendency to rise results in an accumulation of vapor which forces the level down.

While I have shown the inlet ends cut off on a horizontal plane, at right angles to the axes of 10 said inlet ends, it is to be understood that the invention is not so limited. The inlet ends may be of any suitable form, as described below, but they should be identical where equal quantities of liquid refrigerant are desired.

The liquid and vaporous refrigerant then flow through the convolutions or tubes 16 to 23 of the coils, successively. As the liquid passes through the several tubes, it absorbs heat from the air circulated by the fan 12 and is vaporized, 20 and the vaporous refrigerant also absorbs some degree of sensible heat. When the evaporator is used for comfort cooling of air, the temperature of the refrigerant varies between about 30° F. and 50° F. The vaporized refrigerant is dis- 25 charged from the several coils through the tube portions 38' into the suction header 13 to be returned to the compressor for recirculation.

In the modification shown in Fig. 4, each inlet end portion 29a is slotted adjacent the inlet end, 30 as shown at 46. The liquid refrigerant enters the coil entirely or mainly through the slots. With this form, the distribution of liquid refrigerant to the several coils is less affected in case the header is not disposed exactly level or the 35 inlet ends are not at exactly the same level. The liquid level rises to the upper ends of the inlet end portions 29a or adjacent thereto so that, if one inlet end portion is somewhat higher than others, it still has most of its slot below the surface of the liquid and receives substantially its portion of liquid.

In Fig. 5, the upper edges of the inlet end portions 29b are serrated, which form also tends to equalize the flow of liquid into the coils.

While I have shown my invention in three forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In refrigerating apparatus, the combination of an evaporator, a compressor for withdrawing vaporized refrigerant from the evaporator and compressing the same, means for condensing the compressed refrigerant, expansion valve means 60 for reducing the pressure of the condensed refrigerant and discharging the same in the form of a mixture of liquid and vapor, said evaporator comprising a refrigerant supply header receiving said mixture and a plurality of evaporator pas- 65 sages, the inlet ends of said evaporator passages opening upwardly into said header at substantially the same level intermediate the upper and lower extremities of the interior thereof, whereby said passages receive liquid refrigerant sub- 70 stantially in desired predetermined proportions.

2. In refrigerating apparatus, the combination of an evaporator, a compressor for withdrawing vaporized refrigerant from the evaporator and compressing the same, means for condensing the 75

compressed refrigerant, expansion valve means for reducing the pressure of the condensed refrigerant and discharging the same in the form of a mixture of liquid and vapor, said evaporator 5 comprising a refrigerant supply header and a plurality of evaporator passages, means for conveying said mixture of liquid and vaporous refrigerant through said supply header and through said evaporator passages, said evaporator passages having inlet end portions, each of 10 equal perimeter, opening upwardly into said supply header at substantially the same level intermediate the upper and lower extremities of the interior thereof, whereby said evaporator passages receive vapor and liquid refrigerant substantially in equal proportions.

3. In refrigerating apparatus, the combination of a plurality of evaporator passages, a refrigerant supply header therefor, means for delivering a mixture of vapor and liquid refrigerant to said header and means to distribute the mixture of vapor and liquid refrigerant to the evaporator passages in equal proportions, said last-mentioned means comprising the inlet end portions of said evaporator passages, which portions project upwardly into said supply header and terminate in equal perimeters at substantially the same level intermediate the upper and lower extremities of the interior thereof.

30 4. In refrigerating apparatus, the combination of a plurality of evaporator passages, a refrigerant supply header therefor, means for delivering a mixture of vapor and liquid refrigerant to said header and means to distribute the mixture of vapor and liquid refrigerant in predetermined proportions to the evaporator passages, said last-mentioned means comprising the inlet end portions of said evaporator passages, which portions project upwardly into said supply header and terminate at substantially the same level intermediate the upper and lower extremities of the interior thereof.

35 5. In refrigerating apparatus having a plurality of evaporator elements, a device for distributing a mixture of liquid and vaporous refrigerant in predetermined proportions to the evaporator elements comprising a header having an inlet for the mixture of liquid and vaporous refrigerant and a plurality of conduits extending upwardly into said header and having openings communicating with the interior of the header, the openings being similarly formed and the lowest points thereof being disposed substantially

above the bottom and below the top of the interior of the header and at the same level, said conduits communicating with the respective evaporator elements.

6. In refrigerating apparatus having a plurality of evaporator elements, a device for distributing a mixture of liquid and vaporous refrigerant in predetermined proportions to the evaporator elements comprising a header having an inlet for the mixture of liquid and vaporous refrigerant and a plurality of conduits extending vertically into said header and communicating with the respective evaporator elements, said conduits having relatively narrow, vertically elongated openings communicating with the interior of said header, the lowermost points of said openings being disposed substantially above the bottom and below the top of the interior of said header and at the same level.

7. In refrigerating apparatus having a plurality of evaporator elements, a device for distributing a mixture of liquid and vaporous refrigerant in predetermined proportions to the evaporator elements comprising a header having an inlet for the mixture of liquid and vaporous refrigerant and a plurality of conduits extending upwardly into said header and having openings communicating with the interior of the header, the lowermost points of said openings being disposed above the bottom and below the top of the interior of the header and at the same level, said conduits communicating with the respective evaporator elements.

30 8. In refrigerating apparatus having a plurality of evaporator elements, a device for distributing a mixture of liquid and vaporous refrigerant in predetermined proportions to the evaporator elements comprising a header having an inlet for the mixture of liquid and vaporous refrigerant and a plurality of conduits extending upwardly into said header and having openings communicating with the interior of the header, the lowermost points of said openings being disposed at the same level and said openings being of such size and disposition as to maintain a liquid level in said header below the top and above the bottom of the interior of the header, whereby the liquid refrigerant is divided by said openings in predetermined proportions, said conduits communicating with the respective evaporator elements.

FRANK P. TAUGHER.
